Primary Examiner — Austin Murphy(74) *Attorney, Agent, or Firm* — Lewis Roca Rothgerber
Christie LLP(57) **CLAIM**

The ornamental design for a display module, as shown and described.

DESCRIPTION

FIG. 1 is a front-top perspective view of a display module;
 FIG. 2 is a front view of the display module;
 FIG. 3 is a rear view of the display module;
 FIG. 4 is a left-side view of the display module;
 FIG. 5 is a right-side view of the display module;
 FIG. 6 is a top view of the display module;
 FIG. 7 is a bottom view of the display module;
 FIG. 8 is a rear-top perspective view of the display module;
 FIG. 9 is a cross-sectional view of the display module taken along the line A-A' of FIG. 2;
 FIG. 10 is a front-top perspective view of the display module with the color omitted to better show the curvature of the display module; and,
 FIG. 11 is a front view of the display module of FIG. 10. The broken lines illustrate environmental structure that forms no part of the claimed design.
